G. LEE

ROCK DRILL

Filed June 18, 1926

INVENTOR.
Gordon Lee.
BY *Herbert C. Ode*
HIS ATTORNEY.

UNITED STATES PATENT OFFICE.

GORDON LEE, OF EASTON, PENNSYLVANIA, ASSIGNOR TO INGERSOLL-RAND COMPANY, OF JERSEY CITY, NEW JERSEY, A CORPORATION OF NEW JERSEY.

ROCK DRILL.

Application filed June 18, 1926. Serial No. 116,910.

This invention relates to rock drills, but more particularly to a pressure fluid controlling device for fluid actuated rock drills of the hand held type.

5 The objects of the invention are to enable the pressure fluid controlling means to be actuated in an improved and simplified manner, to reduce the number of parts of the devices of this character to a minimum and 10 to protect the handle of the drill against breakage.

Other objects will be in part obvious and in part pointed out hereinafter.

The invention consists of the combination 15 of elements and arrangement of parts having the general mode of operation substantially as hereinafter described and more particularly pointed out in the appended claims and illustrated in the accompanying drawings, in which—

Figure 1 is a sectional elevation of so much of a rock drill as will serve to illustrate the invention,

Figure 2 is a sectional view taken through Figure 1 on the line 2—2 looking in the direction of the arrows, and

Figure 3 is a transverse view taken through Figure 1 on the line 3—3 looking in the direction of the arrows.

30 Referring to the drawings, the invention is shown embodied in a rock drill having a cylinder A provided with a free exhaust port B. A hammer piston C is adapted to reciprocate in the cylinder A for the purpose of delivering blows to a drill steel D extending into a front head E. The rearward end of the cylinder A in this instance is closed by a back head F upon which is seated a handle G having grip portions H and J whereby the rock drill may be guided. A suitable closure for the front end of the cylinder is provided by a front cylinder washer K having rearward and forward extensions L and O to extend into the cylinder 35 A and the front head E respectively for centralizing these parts with respect to each other. In addition to serving the functions hereinbefore set forth, the front cylinder washer K also acts as a guide and a seat for an anvil block P interposed between the piston C and the drill steel D for transmitting the blows of the piston to the drill steel.

Any suitable means may be provided for holding the parts comprising the casing as 50 well as the handle G of the drill in as-

sembled relation, such means, however, preferably consisting of the usual side bolts (not shown).

Pressure fluid for actuating the piston C may be conveyed from a source of supply 60 by any suitable means to a chamber Q preferably formed at the rearward end of the cylinder A and which chamber communicates with the rearward end of a piston chamber R through a passage S in the back 65 head F.

The piston illustrated in the drawings is of the type adapted to control the distribution of the pressure fluid to the opposite ends of the cylinder for actuating the piston and has a rearward extension T, the rearward end of which is constantly exposed to pressure fluid during the operation of the drill. In this instance, pressure fluid for impelling the piston forwardly is conducted 70 from the rearward end of the chamber R through a passage U to a point near the forward end of the chamber R. Pressure fluid thus admitted through the passage U may flow around a reduced portion V of the 75 extension T into the rearward end of a main piston chamber W. The admission of pressure fluid to the front end of the chamber W is in this instance effected through a passage X leading from the front end of the 80 cylinder to communicate with the chamber R at a point intermediate the ends of the passage U. The passage X, like the passage U, is also controlled by the piston extension D and the rearward end thereof is so 85 positioned with respect to the chamber R that at about the time the hammer piston delivers its blow to the anvil block P, pressure fluid will flow through the passage X into the front end of the cylinder for impelling 90 the piston rearwardly.

The admission of pressure fluid from the chamber Q into the passage S is controlled by a throttle valve Y which is adapted to seat on a valve seat Z formed at the opening of the passage S adjacent the chamber Q. A spring b seated with one end on the bottom of the chamber Q and with its other end on the valve Y serves to hold the valve 95 on its seat.

In accordance with the practice of the invention, the grip J is formed of smaller external diameter than the grip H thus forming a shoulder c at the inner end of the grip J to act as an abutment for a hollow cup- 100 105 110

shaped sleeve *d* adapted to rotate on the grip *J*. At the inner end of the sleeve *d* is formed a cam *e* to encircle said sleeve and is adapted to rotate through a slot *f* in the rearward face of the back head *F*. The slot *f* is preferably directly in line with the valve seat *Z* and is of such width that its sides engage slidably the sides of the cam *e* for preventing endwise movement of the sleeve 10 on the grip *J*. A stem *g* carried by the valve is guided in a bore *h* between the valve seat *Z* and the slot *f* and extends with its free end into the slot *f*. The stem *g* is preferably of such length that when the cam *e* is 15 in its inoperative position, a slight clearance will exist between the stem and the end of the cam.

Means are preferably provided for limiting rotative movement of the sleeve *d* on 20 the grip *J*. A convenient means of accomplishing this is illustrated in Figures 1 and 3 in which a pin *k* is secured to an end wall *o* of the sleeve *d* and has an inwardly extending portion *p* rotatable in an annular 25 slot *q* formed in the end of the grip *J*. Shoulders *r* and *s* are preferably formed at the ends of the slot *q* to act as abutments for the portion *p* of the pin *k*.

In assembling the device, the sleeve *d* may 30 first be disposed on the grip *J* in the manner illustrated in the drawings. The handle *G* may then be placed on the back head *F* in a position to enable the cam *e* to be inserted in the slot *f*. Thereafter the side 35 bolts or screws, such as are commonly used for the purpose, may be secured to the drill for clamping the handle and the back head in operative position to the cylinder *A*.

In the operation of the device; whenever 40 it is desired to admit pressure fluid into the cylinder *A* for reciprocating the piston *C*, the sleeve *d* may be rotated in a clockwise direction as viewed from the right hand side of the figures. Such rotation of the sleeve 45 will cause the cam *e* to ride on the free end of the stem *g* and will thus unseat the valve *Y*. Continued rotation in this direction of the sleeve *d* will carry the portion *p* of the pin *k* against the shoulder *s* in the slot *q*. In this position of the sleeve, the valve *Y* 50 will be fully opened and the valve may be thus held during the normal operation of the drill unaffected by the jars and shocks set up by the drill. Whenever it is desired 55 to cut off the supply of pressure fluid from the drill, the sleeve *d* may be rotated in a counter-clockwise direction to move the cam *e* out of contact with the stem *g* of the valve *Y* and the valve will then be forced 60 quickly to its seat by the spring *b*.

The advantages of this invention reside chiefly in the fact that the perimetric surfaces of the grip portions *H* and *J* remain unbroken throughout their lengths. This construction renders these grip portions 65 strong and eliminates the chances of breakage which frequently occurs in drills of this type. By means of the controlling mechanism hereinbefore described, the amount of pressure fluid to the rock drill 70 may be accurately and efficiently controlled. Another desirable advantage of this construction over other well known devices of this character is that the operator may at all times apply full pressure to the handle of 75 the drill with both hands without necessitating the frequent release of one of the grips or a change of the position of his hands for the purpose of manipulating the pressure fluid controlling element. 80

I claim:

1. In a rock drill, the combination of a cylinder, a back head therefor, a throttle valve controlling the admission of pressure fluid to the cylinder, a handle secured to the back head for guiding the drill, a sleeve rotatable on the handle, a cam on the sleeve for manipulating the throttle valve, and a slot in the back head cooperating with the cam for holding the sleeve on the handle. 90

2. In a rock drill, the combination of a cylinder, a back head for the cylinder having a slot in one side, a throttle valve controlling the admission of pressure fluid to the cylinder, a handle secured to the back head for 95 guiding the drill, a sleeve rotatable on one end of the handle, and a cam encircling one end of the sleeve for unseating the valve, said cam being engaged by the slot to hold the sleeve against removal from the handle. 100

3. In a rock drill, the combination of a cylinder, a back head for the cylinder having a slot in one side, a valve seat on the opposite side of the back head and in line with the slot, a throttle valve in the back head adapted to cooperate with the seat to control the admission of pressure fluid into the cylinder, a stem on the valve extending into the slot, a handle secured to the back head for guiding the drill, a sleeve rotatable on the handle, and a cam encircling one end of the sleeve and integral therewith to cooperate with the stem for unseating the valve, said cam being rotatable through the slot whereby it is engaged for holding the 110 sleeve against endwise movement. 115

In testimony whereof I have signed this specification.

GORDON LEE.
